UNITED STATES PATENT OFFICE

FLOY C. MERRILIES, OF CHICAGO, ILLINOIS

DESIGN FOR A LADY'S NECKPIECE

Application filed September 24, 1930. Serial No. 37,066. Term of patent 14 years.

To all whom it may concern:

Be it known that I, FLOY C. MERRILIES, a citizen of the United States, residing at Chicago, county of Cook, Illinois, have invented a new, original, and ornamental Design for Lady's Neckpiece, of which the following is a specification, reference being had to the accompanying drawing, forming a part thereof.

The figure is a front view of my new design of a neckpiece. The neckpiece is composed of a fabric made up of yarn having a very long nap or hairy surface which is suggestive in appearance of an animal pelt.

I claim:

The ornamental design for a lady's neckpiece as shown and described.

FLOY C. MERRILIES.
